LEO T. HUNSTIGER, OF CHICAGO, ILLINOIS

DISPLAYING-SHELF BRACKET

Application filed June 20, 1927. Serial No. 200,251.

This invention relates to certain novel improvements in displaying shelf brackets.

The salient object of my invention is to provide a bracket adapted to support display shelves of glass or similar material and my improvement consists in providing an arrangement whereby a plurality of shelves may be suspended in vertical alignment.

Other objects will appear hereinafter.

10 The invention consists in the novel combination and arrangement of parts to be hereinafter described and claimed.

The invention will be best understood by reference to the accompanying drawings, 15 showing the preferred form of construction and in which:

Fig. 1 is a front elevational view of two shelves supported by my improved brackets;

Fig. 2 is a sectional view taken substantially in the plane of the line 2—2 on Fig. 1;

Fig. 3 is an elevational view of one embodiment of a bracket employed in the construction depicted in Figs. 1 and 2; and

Fig. 4 is an elevational detail view of a 25 modified form of bracket construction.

In the construction of store fronts it frequently occurs that a portion of the show window is comparatively narrow and merchants in displaying goods in these narrow portions have found it advantageous to provide shelves in these spaces and to mount the goods to be displayed on these shelves. Further, in displaying certain kinds of merchandise it has been found advantageous to employ shelves in the show windows in order to support the merchandise. Especially in the case of the narrow show window it has been found difficult to properly locate the goods on the shelves in order to advantageously display them. The shelves used are usually constructed of glass and are supported one upon the other by suitable standards. This method of supporting the shelves embodied numerous disadvantages due to the fact that the standards occupied space which might be used for displaying purposes and they also added to the difficulty of placing articles upon the shelves when said shelves were located in the described narrow points of the 50 show window.

In view of the foregoing disadvantages I have provided a method whereby the shelves may be suspended from the top of the show window by means of chains. In order to accomplish this I provide a bracket 10 which embodies upwardly extending lugs such as 11 and 12 on the ends thereof. The shelf 13 is mounted on the bracket 10 and the lugs 11 and 12 serve to prevent displacement of the shelf. Suitable openings such as 14 are provided in the upwardly extending lugs and suitable chains 15 are positioned so as to have links thereof retained in the openings 14 and the chains 15 are then attached to suitable supporting members (not shown) provided on the top of the show window or other point where it is desired to mount the shelves. The foregoing construction serves to support only one shelf and I have found it advantageous to support more than one and in order to accomplish this I provide on the lower side of the bracket 10 so as to be disposed opposite the lugs 11 and 12 suitable supporting elements such as 16. Suitable chains such as 15' are then secured in the supporting elements 16 and the lower ends of the chains 15' are attached to other brackets 10 in the manner that has been described. In this way I am enabled to support any desired number of shelves from a single point.

In Fig. 3 I have illustrated one form of the securing elements 16 and I show herein an eye which is adapted to be secured to the bracket 10 in any suitable manner such as by providing a suitable hole in the bracket 10 and then inserting a portion of the eye therein and then riveting the eye in position. It is to be understood however that any other desired method might be employed for mounting the supporting elements 16 in position. Further, hook members might be substituted for the eyes and still not depart from the spirit and scope of my invention and as will be apparent to anyone skilled in the art other suitable supporting elements might be substituted for the eyes shown and hooks mentioned.

In Fig. 4 a modified form of bracket construction is shown. Herein a bracket 17 is provided which embodies a vertically extend-

ing lug 18 and at the connection between the horizontal portion 17 and the vertical portion 18 the member 17 is bent downwardly so as to form a recess 19. The link 20 of the chain 15' 5 is then inserted over the vertically extending portion 18 and is disposed so as to rest in the recess 19 substantially as shown in Fig. 4. This modified form of bracket embodies numerous advantages over the one disclosed in 10 Fig. 3 for it may be formed of a single piece of metal that may be stamped so as to embody the desired configuration.

It is to be understood that while I have shown herein the vertically extending lugs 15 as being formed as part of the bracket angle clips may be substituted therefor and be suitably secured to the horizontal portion of the bracket 10. Further, if desired the supporting elements 16 may be formed in the following 20 manner. The vertically extending portion of the bracket 17 may be made of greater length and the added portion thereof may then be bent back along the vertically extending portion so as to embody a portion disposed below the bracket 17 and then the chain 15 may be secured to this downwardly protruding portion.

It is to be understood that while I have shown herein but two modifications of my invention that this may be varied in many ways and still not depart from the purview of my invention.

As is clearly shown in Fig. 2 it is frequently desirable that the shelves 13 be of different 35 widths. When such a construction is employed the narrowest width is mounted at the top and then the next succeeding width is spaced therefrom and mounted below it and then the succeeding widths are mounted in 40 this manner. It is apparent from this that the brackets 10 will be provided of a plurality of sizes so as to accommodate shelves of varied widths. However, it is to be distinctly understood that shelves of the same width might 45 be mounted in the foregoing manner and still not depart from the spirit and scope of my invention.

While I have illustrated and described the preferred form of construction for carrying 50 my invention into effect, this is capable of variation and modification, without departing from the spirit of the invention. I, therefore, do not wish to be limited to the precise details of construction set forth, but desire to avail 55 myself of such variations and modifications as come within the scope of the appended claim.

Having thus described my invention what 60 I claim as new and desire to protect by Letters Patent is:

A shelf supporting bracket member comprising a flat strip having up-turned portions at the ends thereof, said up-turned portions having openings provided therein adjacent 65 the upper ends thereof in which supporting

elements may be secured to support said strip, said strip having openings provided therein adjacent said up-turned portions, and elements including stem portions adapted to be secured in said last named openings, said elements comprising substantially loop shaped portions adapted to be disposed to depend below said strip.

In testimony whereof I affix my signature.

LEO T. HUNSTIGER.
